UNITED STATES PATENT OFFICE.

JAMES EDWARD PULLIAM, OF PORT WASHINGTON, NEW YORK.

CORN-PROTECTOR.

1,079,347.

Specification of Letters Patent. Patented Nov. 18, 1913.

Application filed January 11, 1912. Serial No. 670,616.

To all whom it may concern:

Be it known that I, JAMES EDWARD PULLIAM, a citizen of the United States, and a resident of Port Washington, Nassau county, New York, have invented new and useful Improvements in Corn-Protectors, of which the following is a specification.

My invention relates to a corn shield and one that is adapted to protect or shield a corn that is liable to contact or be rubbed against by an adjacent toe.

One object of the invention is to provide a device of this kind that may be made of yielding material such as rubber, and be of such construction that it will be securely held in place between the toes.

Another object of the invention is to provide a device of this kind that is, as may be gathered from the foregoing, of simple construction and a device which may be manufactured at an exceedingly low cost.

Other objects of the invention, mostly minor in nature, will appear from the description of the invention following, taken in connection with drawings accompanying this application, and illustrating the preferred embodiment of the invention.

In said drawings:—Figure 1 is a perspective view illustrating the device as used to protect a corn, a foot also being shown fragmentarily and in dotted lines; Fig. 2 is a transverse sectional view through the same parts, but showing the shield in elevation, and a shoe fragmentarily and in section; Fig. 3 is a perspective view of the shield; Fig. 4 is a vertical sectional view of the shield, and, Fig. 5 is a vertical sectional view of the shield taken at right angles to Fig. 4.

Like reference characters designate like parts throughout the several views of the drawings.

Referring specifically to the drawings, 1 designates a shoe, 2 designates toes of a foot, and 3 generally designates my improved shield. Said shield comprises a body preferably made of rubber or other yielding material so as to have a cushioning action against the toes between which it is located. If desired, said body may be reinforced by any suitable means such as by rods designated 4 and embedded or driven into the shield.

On each face the shield is concaved at the center as at 5, and to said concaved portion 55 slant walls designated 6. It will thus be seen that each face of the shield is cut away or substantially concaved so as to conform to the curvature or shape of the toes.

At one edge the shield is concaved as at 7, 60 and to the concaved portion slant walls designated 8 so as to provide a concaved or cut out portion to conform to the shape of the foot at the junction of the toes.

The device as stated, is principally adapted to protect or shield a corn that is likely to contact with or be rubbed against by an adjacent toe. The device or shield is inserted between the toes, as shown in Figs. 1 and 2, the toes bearing or resting in the 70 concaved portions 5. Also that portion of the foot at the junction of the toes, bears against the concaved portion 7. The walls 6 and 8, by reason of their inclination, it will be noted, extend outwardly beyond the 75 concaved portions and above the portions of the toes and foot, respectively, which engage the shield. Said walls serve to prevent disengagement of the shield from the toes in a vertical plane. By reason of the usual 80 shape of the shoe, the same usually will bear against the shield and serve to some extent, to maintain the same in position. By reason of the resilient or yielding action of the shield, the toes are cushioned.

It will be seen that the shield will effectively prevent contact or rubbing of a corn against an adjacent toe or part of a shoe, and that the same is exceedingly simple in construction and hence may be manufactured at an exceedingly low cost.

As changes in the details of construction of my preferred embodiment may suggest themselves, the right to make such changes within the spirit and scope of the appended 95 claims is accordingly reserved.

Having thus fully described my said invention, what I claim as new and desire to secure by Letters Patent is:—

1. A device of the class described comprising a shield made of rubber having a concaved face on one edge, walls in continuation of and extending beyond said face, said shield having concaved faces on opposite sides of the shield, walls in continuation of and extending beyond said latter

faces, and reinforcing rod means interior of said shield.

2. In a device of the character described, a body portion comprising a rubber shield, said shield having a concave face on one edge, the opposite side faces of said shield being concaved, and reinforcing means in-

cluding spaced-apart rods extending vertically within said shield, substantially as described.

JAMES EDWARD PULLIAM.
